UNITED STATES PATENT OFFICE.

ROY X. TUTTLE, OF BATTLE CREEK, MICHIGAN.

THERAPEUTIC LAMP.

Application filed February 5, 1927. Serial No. 166,175.

The main object of this invention is to provide an improved therapeutic lamp well adapted for the production of infra-red rays which is highly efficient, durable and not 5 likely to get out of repair.

A further object is to provide a lamp having these advantages which is comparatively economical in structure.

Objects pertaining to details and economies of my invention will definitely appear 10 from the detailed description to follow. The invention is clearly defined and pointed out in the claims.

A structure which is a preferred embodiment of my invention is clearly illustrated 15 in the accompanying drawing forming a part of this application, in which:

Fig. 1 is a side elevation of my improved lamp, one of the tubular radiating elements 20 being shown in longitudinal section on line 20 1—1 of Fig. 2.

Fig. 2 is a transverse section through one unit of the lamp on a line corresponding to line 2—2 of Fig. 1.

Fig. 3 is a side elevation of parts of the lamp illustrating structural details.

Fig. 4 is a side elevation of one of the resistance cores with a portion of the resistance indicated thereon.

Fig. 5 is a side view of one of the tubular radiating elements.

Referring to the drawing I provide a base member 1, preferably a casting, having outwardly diverging arms 2. The threaded plug shell 3 is mounted on this base member. The central terminal 4 of the socket plug is extended into a shell 5. The arms have holes 6 therein in which the flanged insulating bushings 7 are arranged, insulating disks 7' being arranged on the under sides of the arms.

The posts 8 are threaded at each end and are provided with clamping nuts 9 and 10 at their lower ends engaging the inner and outer sides of the insulating material described whereby the posts are rapidly mounted on the arms. The upper ends of the posts are connected by the cross piece 11 and the posts are threaded into this cross piece.

Loosely arranged on the posts are cores 12. Resistance coils 14 are wound upon the cores, the upper ends of these resistance coils being connected by the connecting wire 15 which is secured to the under side of the cross piece 11 at 16. The inner end 17 of one of the coils is connected to the post 5 while the

inner end 18 of the other coil is connected to the base by the binding screw 19.

The tubular radiating elements 20 which are formed of what is commercially known as "lava" surround the coils to be heated to incandescence thereby. These tubes 20 have longitudinal slits 21 therein. The cores and the radiating elements are arranged on the posts between the base and cross piece in 60 non-clamping relation, that is, they are sufficiently loose to permit expansion, thereby preventing breakage. The longitudinal slits also permit expansion and contraction without danger of breaking the radiating elements, which are formed of earthy material and consequently might be fractured if they were rigidly clamped, although the longitudinal slits reduce the likelihood of fracture 65 70 75

My improved lamp is very economical to produce, may be used with the desired reflector in an ordinary lamp socket and is highly efficient.

Having thus described my invention what 80 I claim as new and desire to secure by Letters Patent is:

1. In a device of the class described, the combination with a socket plug provided with a centrally disposed terminal post and having outwardly diverging arms with openings therein, insulating bushings disposed in said openings in said arms, a top cross piece, posts threaded into said cross piece and having their lower ends disposed through said bushings, said posts being provided with clamping nuts above and below said bushings whereby they are rigidly mounted on said arms, cylindrical cores arranged on said posts, resistance coils on 85 90 95 said cores, said coils being electrically connected at their outer ends, the inner end of one of said coils being connected to said terminal post and the other to one of said arms, and tubular radiating elements surrounding said cores and resistance coils, said radiating elements having longitudinal slits therein and being loosely supported between said arms and cross piece.

2. In a device of the class described, the 100 105 combination with a socket plug provided with a centrally disposed terminal post and having outwardly diverging arms with openings therein, insulating bushings disposed in said openings in said arms, a top cross piece, posts threaded into said cross piece and having their lower ends disposed 110

through said bushings, said posts being provided with clamping nuts above and below said bushings whereby they are rigidly mounted on said arms, cylindrical cores arranged on said posts, resistance coils on said cores, said coils being electrically connected at their outer ends, the inner end of one of said coils being connected to said terminal post and the other to one of said arms, and 10 tubular radiating elements surrounding said cores and resistance coils.

3. In a device of the class described, the combination with a socket plug provided with a centrally disposed terminal post and 15 having forwardly diverging arms with openings therein, posts mounted on said arms and insulated therefrom, a cross piece connecting said arms, cylindrical cores arranged on said posts, resistance coils on said cores, said 20 coils being electrically connected at their outer ends, the inner end of one of said coils being connected to said terminal post and the other to one of said arms, and tubular radiating elements surrounding said 25 cores and resistance coils, said radiating elements having longitudinal slits therein and being loosely supported between said arms and cross piece.

4. In a device of the class described, the combination with a socket plug provided with a centrally disposed terminal post and having forwardly diverging arms with openings therein, posts mounted on said arms and insulated therefrom, a cross piece connecting said arms, cylindrical cores arranged on said posts, resistance coils on said cores, said coils being electrically connected at their outer ends, the inner end of one of said coils being connected to said terminal post and the other to one of said arms, and tubular radiating elements surrounding said cores and resistance coils.

5. In a device of the class described, the

combination with the base member provided with a socket plug, posts mounted on said base member and insulated therefrom, a cross piece connecting the outer ends of said posts, the base member, cross piece and posts constituting a rigid frame, cores arranged on said posts, resistance coils on said cores electrically connected to said socket plug, and tubular radiating elements embracing said coils and cores, said radiating elements having longitudinal slits therein and being disposed in non-clamping relation between 55 said arms and cross piece.

6. In a device of the class described, the combination with the base member provided with a socket plug, posts mounted on said base member and insulated therefrom, a cross piece connecting the outer ends of said posts, the base member, cross piece and posts constituting a rigid frame, cores arranged on said posts, resistance coils on said cores electrically connected to said socket plug, 60 and tubular radiating elements embracing said coils and cores.

7. In a device of the class described, the combination with the base member provided with a socket plug, posts mounted on said base member and insulated therefrom, a cross piece connecting the outer ends of said posts, cores arranged on said posts, and resistance coils on said cores electrically connected to 70 said socket plug.

8. In a device of the class described, the combination with the base member, posts mounted on said base member and insulated therefrom, a cross piece connecting the outer ends of said posts, the base member, cross piece and posts constituting a rigid frame, and radiating elements including resistance coils mounted on said posts.

In witness whereof I have hereunto set my hand.

ROY X. TUTTLE.
